(57) **ABSTRACT**

To achieve a high inductance value while reducing the entire thickness in a coil component having a structure in which spiral coil patterns are stacked. A coil component includes: a coil part having a structure in which interlayer insulating films and spirally wound coil patterns are alternately stacked in the axial direction of the coil component; and magnetic element members embedding therein the coil part. The interlayer insulating film covering, from one end side in the axial direction, one coil pattern positioned at the one end in the axial direction is higher in permeability than the interlayer insulating films. Thus, the one coil pattern positioned at the end portion is covered with the interlayer insulating film having a high permeability, so that it is possible to achieve a high inductance value while reducing the entire thickness.

COIL COMPONENT AND MANUFACTURING
METHOD THEREFORCROSS REFERENCE TO RELATED
APPLICATIONS

This application is the U.S. National Phase under 35 U.S.C. § 371 of International Application No. PCT/JP2021/004965, filed on Feb. 10, 2021, which claims the benefit of Japanese Patent Application No. 2020-024126, filed on Feb. 17, 2020, the entire contents of each are hereby incorporated by reference.

TECHNICAL FIELD

The present invention relates to a coil component and a manufacturing method therefor and, more particularly, to a coil component having a structure in which spiral coil patterns are stacked one on another and a manufacturing method for such a coil component.

BACKGROUND ART

As a coil component having a structure in which spiral coil patterns are stacked, a coil component described in Patent Document 1 is known. The coil component described in Patent Document 1 has a structure in which a coil pattern is embedded in a first magnetic resin layer containing spherical magnetic filler, and the coil pattern is sandwiched in the stacking direction by second magnetic resin layers containing flat magnetic filer.

The coil component described in Patent Document 1 has a structure in which the coil pattern is embedded in the magnetic resin layer as described above and thus can achieve a high inductance value.

CITATION LIST

Patent Document

[Patent Document 1] JP 2019-140202A

SUMMARY OF THE INVENTION

Problem to be Solved by the Invention

However, in Patent Document 1, the second magnetic resin layers are disposed outside the first magnetic resin layer, which disadvantageously increases the thickness of the entire coil component.

It is therefore an object of the present invention to achieve a high inductance value while reducing the entire thickness in a coil component having a structure in which spiral coil patterns are stacked and a manufacturing method therefor.

Means for Solving the Problem

A coil component according to the present invention includes: a coil part having a structure in which a plurality of interlayer insulating films and a plurality of spirally wound coil patterns are alternately stacked in the axial direction; and a magnetic element member embedding therein the coil part. The plurality of interlayer insulating films include a first interlayer insulating film covering, from one end side in the axial direction, a first coil pattern of the plurality of coil patterns that is positioned at the one end in the axial direction and second interlayer insulating films

2

covering the remaining coil patterns of the plurality of coil patterns. The first interlayer insulating film is higher in permeability than the second interlayer insulating films.

According to the present invention, the first coil pattern positioned at the end portion is covered with the first interlayer insulating film having a high permeability, so that it is possible to achieve a high inductance value while reducing the entire thickness.

In the present embodiment, the magnetic element member 10 may be higher in permeability than the first interlayer insulating film. This can achieve a higher inductance value. Further, when a material having a thermal expansion coefficient close to that of the magnetic element member is used for the first interlayer insulating film, it is possible to prevent 15 peeling at the interface between the first interlayer insulating film and the magnetic element member.

In the present invention, the first interlayer insulating film 20 may be made of the same material as the magnetic element member. This makes the thermal expansion coefficient of the first interlayer insulating film and that of the magnetic element member coincide with each other, thereby making it possible to prevent peeling at the interface between the first interlayer insulating film and the magnetic element member more effectively.

In the present invention, the first interlayer insulating film 25 may be made of a magnetic resin material obtained by adding magnetic filler to a resin material, and the maximum particle size of the magnetic filler may be smaller than the pattern interval of the first coil pattern. This allows the magnetic filler to enter between the patterns of the first coil pattern, making it possible to achieve a higher inductance value.

In the present invention, the magnetic filler may contain 35 nanofiller made of a magnetic metal member having a mean particle size of 1 μm or less. This allows the magnetic filler to enter between the patterns of the first coil pattern more easily.

In the present invention, the first coil pattern may be 40 tapered such that a cross section of the first coil pattern is narrower toward the one end side in the axial direction. This allows the magnetic filler to enter between the patterns of the first coil pattern more easily.

In the present invention, the coil part may include an 45 electrode pattern positioned in the same conductor layer as the first coil pattern, and the electrode pattern may contact the first interlayer insulating film and may be exposed from the magnetic element member. This enhances heat dissipation performance of the coil component.

In the present invention, the plurality of interlayer insulating films 50 may further include a third interlayer insulating film covering, from the other end side in the axial direction, a second coil pattern of the plurality of coil patterns that are positioned at the other end in the axial direction, and the third interlayer insulating film may be higher in permeability than the second interlayer insulating film. Thus, the third coil pattern positioned at the end portion is covered with the third interlayer insulating film having a high permeability, so that it is possible to achieve a high inductance value while reducing the entire thickness.

A coil component manufacturing method according to the 55 present invention includes: a first step of alternately stacking a plurality of interlayer insulating films and a plurality of spirally wound coil patterns in the axial direction to form a coil part; and a second step of embedding the coil part in a magnetic element member. The plurality of coil patterns includes a first coil pattern to be formed last and remaining second coil patterns. The plurality of interlayer insulating

films include first and second interlayer insulating films. The first step includes a step of alternately forming the second coil patterns and the second interlayer insulating films and a step of, after forming the first coil pattern, covering the first coil pattern with the first interlayer insulating film. The first interlayer insulating film is higher in permeability than the second interlayer insulating film.

According to the present invention, the first coil pattern positioned at the end portion is covered with the first interlayer insulating film having a high permeability, thereby making it possible to manufacture a coil component having a small thickness as a whole and a high inductance value.

Advantageous Effects of the Invention

As described above, according to the present invention, it is possible to achieve a high inductance value while reducing the entire thickness in a coil component having a structure in which spiral coil patterns are stacked and a manufacturing method therefor.

BRIEF DESCRIPTION OF THE DRAWINGS

FIG. 1 is a schematic cross-sectional view for explaining the structure of a coil component 1 according to an embodiment of the present invention.

FIG. 2 is a partial cross-sectional view of the coil part C.

FIG. 3 is a process view for explaining the manufacturing method for the coil component 1.

FIG. 4 is a process view for explaining the manufacturing method for the coil component 1.

FIG. 27 is a process view for explaining the manufacturing method for the coil component 1.

MODE FOR CARRYING OUT THE INVENTION

Hereinafter, preferred embodiments of the present invention will be described in detail with reference to the accompanying drawings.

FIG. 1 is a schematic cross-sectional view for explaining the structure of a coil component 1 according to an embodiment of the present invention.

The coil component 1 according to the embodiment of the present invention is a surface-mount type chip component suitably used as an inductor for a power supply circuit and has, as illustrated in FIG. 1, a magnetic element members M1 to M3 and a coil part C embedded in the magnetic element members M1 to M3. Although the configuration of the coil part C will be described later, in the present embodiment, four conductor layers each having a spiral coil pattern are stacked through interlayer insulating films to form one coil conductor.

The magnetic element members M1 to M3 are each a composite member containing magnetic metal filler made of iron (Fe) or a permalloy-based material and a resin binder and form a magnetic path of magnetic flux generated by a current flowing in the coil part C. The resin binder is preferably epoxy resin in the form of liquid or powder. The magnetic element members M1 to M3 may be made of the same material or mutually different materials. The magnetic element member M1 is a part filled in the inner diameter area of the coil part C, the magnetic element member M2 is a part covering the coil part C from one side (lower side in FIG. 1) in the axial direction of the coil part C, and the magnetic element member M3 is a part covering the coil part C from the other side (upper side in FIG. 1) in the axial direction.

As illustrated in FIG. 1, the coil part C has alternately stacked interlayer insulating films 51 to 55 and conductor layers 10, 20, 30, and 40. The conductor layers 10, 20, 30, and 40 have spiral coil patterns CP1 to CP4, respectively, and the upper or lower surfaces of the coil patterns CP1 to CP4 are covered with the interlayer insulating films 51 to 55. The side surfaces of the coil patterns CP1 to CP4 are covered respectively with the interlayer insulating films 52 to 55. The above-mentioned upper and lower surfaces of the coil patterns CP1 to CP4 each refer to surfaces perpendicular to the coil axis, and the side surfaces of the coil patterns CP1 to CP4 each refers to a surface parallel to the coil axis.

The coil patterns CP1 to CP4 are mutually connected through through holes formed in the interlayer insulating films 52 to 54 to constitute a single coil part conductor. The conductor layers 10, 20, 30, and 40 are preferably made of copper (Cu). In the present invention, out of the interlayer insulating films 51 to 55, the interlayer insulating films 51 to 54 are made of a non-magnetic material, and the interlayer insulating film 55 in the uppermost layer is made of a magnetic material. That is, the interlayer insulating film 55 is higher in permeability than the interlayer insulating films

51 to 54. The interlayer insulating film **51** in the lowermost layer may be made of the same magnetic material as the interlayer insulating film **55**.

The conductor layer **10** is the first conductor layer formed on the upper surface of the magnetic element member **M2** through the interlayer insulating film **51** and includes an underlying seed layer **S1**. The conductor layer **10** has the coil pattern **CP1** spirally wound in a plurality of turns and two electrode patterns **11** and **12**. The lower surface of the coil pattern **CP1** is covered with the interlayer insulating film **51**, and the side and upper surfaces thereof are covered with the interlayer insulating film **52**. As illustrated in FIG. 1, in a predetermined cross section, the coil pattern **CP1** and electrode pattern **11** are connected, whereas the electrode pattern **12** is provided independently of the coil pattern **CP1**. The electrode patterns **11** and **12** are exposed from the magnetic element members **M1** to **M3**.

The conductor layer **20** is the second conductor layer formed on the upper surface of the conductor layer **10** through the interlayer insulating film **52** and includes an underlying seed layer **S2**. The conductor layer **20** has the coil pattern **CP2** spirally wound in a plurality of turns and two electrode patterns **21** and **22**. The lower surface of the coil pattern **CP2** is covered with the interlayer insulating film **52**, and the side and upper surfaces thereof are covered with the interlayer insulating film **53**. Both electrode patterns **21** and **22** are provided independently of the coil pattern **CP2**. The electrode patterns **21** and **22** are exposed from the magnetic element members **M1** to **M3**.

The conductor layer **30** is the third conductor layer formed on the upper surface of the conductor layer **20** through the interlayer insulating film **53** and includes an underlying seed layer **S3**. The conductor layer **30** has the coil pattern **CP3** spirally wound in a plurality of turns and two electrode patterns **31** and **32**. The lower surface of the coil pattern **CP3** is covered with the interlayer insulating film **53**, and the side and upper surfaces thereof are covered with the interlayer insulating film **54**. Both electrode patterns **31** and **32** are provided independently of the coil pattern **CP3**. The electrode patterns **31** and **32** are exposed from the magnetic element members **M1** to **M3**.

The conductor layer **40** is the fourth conductor layer formed on the upper surface of the conductor layer **30** through the interlayer insulating film **54** and includes an underlying seed layer **S4**. The conductor layer **40** has the coil pattern **CP4** spirally wound in a plurality of turns and two electrode patterns **41** and **42**. The lower surface of the coil pattern **CP4** is covered with the interlayer insulating film **54**, and the side and upper surfaces thereof are covered with the interlayer insulating film **55**. As illustrated in FIG. 1, in a predetermined cross section, the coil pattern **CP4** and electrode pattern **42** are connected, whereas the electrode pattern **41** is provided independently of the coil pattern **CP4**. The electrode patterns **41** and **42** are exposed from the magnetic element members **M1** to **M3**.

The inner peripheral end of the coil pattern **CP1** and the inner peripheral end of the coil pattern **CP2** are connected through a via conductor constituting a part of the conductor layer **20** and penetrating the interlayer insulating film **52**. The outer peripheral end of the coil pattern **CP2** and the outer peripheral end of the coil pattern **CP3** are connected through a via conductor constituting a part of the conductor layer **30** and penetrating the interlayer insulating film **53**. The inner peripheral end of the coil pattern **CP3** and the inner peripheral end of the coil pattern **CP4** are connected through a via conductor constituting a part of the conductor layer **40** and penetrating the interlayer insulating film **54**. As

a result, the coil patterns **CP1** to **CP4** are connected in series to form a coil conductor having a plurality of turns. The electrode patterns **11**, **21**, **31**, and **41** are used as one external terminal, and the electrode patterns **12**, **22**, **32**, and **42** are used as the other external terminal.

The structure of the coil component **1** according to the present embodiment has been described above. Thus, in the coil component **1** according to the present embodiment, the coil part **C** is embedded in the magnetic element members **M1** to **M3**, so that a high inductance value can be obtained with the magnetic element members **M1** to **M3** serving as a magnetic path. Further, the interlayer insulating film **55** covering the coil pattern **CP4** in the uppermost layer is made of a magnetic material, so that it is possible to further increase an inductance value without additionally providing another magnetic layer. In particular, when the interlayer insulating film **55** has a protruding part **55a** protruding to the inner diameter area of the coil pattern, the protruding part **55a** serves as a magnetic resistance to reduce the inductance value; however, in the coil component **1** according to the present embodiment, since the interlayer insulating film **55** is made of a magnetic material, even if the interlayer insulating film **55** has the protruding part **55a**, such a reduction in inductance value can be suppressed. Further, when the interlayer insulating film **51** in the lowermost layer is made of the same material as the interlayer insulating film **55**, such a reduction in inductance value due to the presence of the protruding part **51a** can be suppressed.

The interlayer insulating film **55** may be a magnetic resin material obtained by adding magnetic filler to a resin material. This allows magnetic characteristics and insulation to be controlled by the type, adding amount, particle size, or the like of the magnetic filler. In order to enhance the magnetic characteristics of the interlayer insulating film **55**, magnetic metal filler made of iron (Fe) or a permalloy-based material can be added as with the magnetic element members **M1** to **M3**; however, the interlayer insulating film **55** directly contacts the coil pattern **CP4** and thus needs to have higher insulation than the magnetic element members **M1** to **M3**. In order to enhance the insulation of the interlayer insulating film **55**, the amount of the magnetic filler to be added to a resin material is made smaller than the amount of the magnetic filler contained in the magnetic element members **M1** to **M3**, or the particle size of the magnetic filler to be added to a resin material is made smaller than the particle size of the magnetic filler contained in the magnetic element members **M1** to **M3**. In this case, the permeability of the interlayer insulating film **55** becomes lower than that of the magnetic element members **M1** to **M3** but is higher than that of a common resin material using a nonmagnetic material, thus making it possible to increase the inductance value. Further, the interlayer insulating film **55** may be made of the same material as the magnetic element members **M1** to **M3** as long as the insulation is maintained.

Further, the interlayer insulating film **55** is made of a material of the same type as the magnetic element members **M1** and **M3**, so that the difference of thermal expansion coefficients can be reduced. This can prevent peeling at the interface between the interlayer insulating film **55** and the magnetic element members **M1** and **M3**. In particular, when the interlayer insulating film **55** and magnetic element members **M1** and **M3** are made of the same material, their thermal expansion coefficients completely coincide with each other, so that peeling at the interface therebetween is much less likely to occur.

The maximum particle size of the magnetic filler contained in the interlayer insulating film **55** is preferably

smaller than the pattern interval of the coil pattern CP4. This allows the magnetic filler to enter between the patterns of the coil pattern CP4, thereby making it possible to achieve a higher inductance value. In particular, when nanofiller made of a magnetic metal body having a mean particle size of 1 μm or less is used, the nanofiller easily enters between the patterns of the coil pattern CP4.

In order to allow the magnetic filler to easily enter between the patterns of the coil pattern CP4, the coil pattern CP4 may be formed into a tapered shape in cross section as illustrated in FIG. 2 which is a partly cross-sectional view. That is, assuming that the pattern interval at the bottom contacting the interlayer insulating film 54 is W2 and that the pattern interval at the upper portion opposite the bottom is W1, the coil pattern CP4 may be tapered in cross section from the bottom to the upper portion so as to satisfy W1>W2. The coil patterns CP1 to CP3 may also have a tapered shape. That is, assuming that the pattern interval at the bottom of each of the coil patterns CP1 to CP3 is W4 and that the pattern interval at the upper portion of each of the coil patterns CP1 to CP3 is W3, W3>W4 may be satisfied. In this case, when the coil pattern CP4 is tapered more significantly, that is, when (W1-W2)>(W3-W4), it is possible to allow the magnetic filler to easily enter between the patterns of the coil pattern CP4 while ensuring a sufficient sectional area for the coil patterns CP1 to CP3.

The following describes a manufacturing method for the coil component 1 according to the present embodiment.

FIGS. 3 to 27 are process views for explaining the manufacturing method for the coil component 1 according to the present embodiment. Although the process views illustrated in FIGS. 3 to 27 each illustrate a cross section corresponding to a single coil component 1, multiple coil components 1 can be produced, in practice, by fabricating individual coil components 1 at a time using an aggregate substrate.

A support 60 having a structure in which metal foils 62 and 63 such as copper (Cu) foils are provided on the surface of a base 61 is prepared (FIG. 3). A peeling layer is provided at the interface between the metal foils 62 and 63. Then, the metal foil 63 is patterned to form a protruding part 63a protruding from the metal foil 63 (FIG. 4).

Then, the interlayer insulating film 51 and a metal foil 64 are formed on the surface of the metal foil 63 having the protruding part 63a (FIG. 5). The interlayer insulating film 51 and metal foil 64 can be formed by a laminate method. As a result, the shape of the protruding part 63a is transferred to the interlayer insulating film 51, and thus the interlayer insulating film 51 has a large thickness area 51A and a small thickness area 51B.

After removal of the metal foil 64 by etching (FIG. 6), electroless plating is performed to form a seed layer S1 on the surface of the interlayer insulating film 51 (FIG. 7). The metal foil 64 may be used as a seed layer in place of forming the seed layer S1; however, the seed layer S1 is preferably as thin as possible, so that a thinner seed layer S1 is preferably newly formed after removal of the metal foil 64.

Then, a resist pattern R1 is formed on the surface of the seed layer S1 (FIG. 8). The resist pattern R1 serves as a negative pattern of the conductor layer 10. In this state, electrolytic plating is performed to grow the seed layer S1 to thereby form the conductor layer 10 (FIG. 9). At this time, a sacrificial pattern VP1 is formed in the inner diameter area of the coil pattern CP1. The position of the resist pattern R1 is adjusted such that the sacrificial pattern VP1 completely

overlaps the small thickness area 51A of the interlayer insulating film 51 and partly overlaps the large thickness area 51B.

After peeling of the resist pattern R1 (FIG. 10), a part of the seed layer S1 that is exposed to the peeling portion of the resist pattern R1 is removed by etching (FIG. 11). As a result, the coil pattern CP1 and sacrificial pattern VP1 are electrically isolated by a slit SL. Subsequently, the interlayer insulating film 52 and a metal foil 65 are formed on the surface of the conductor layer 10 so as to fill the slit SL (FIG. 12). The interlayer insulating film 52 and metal foil 65 can be formed by a laminate method. Then, a resist pattern R2 is formed on the surface of the metal foil 65 (FIG. 13), and the metal foil 65 is etched with the resist pattern R2 used as a mask (FIG. 14). As a result, a part of the metal foil 65 that overlaps the sacrificial pattern VP1 is removed.

After peeling of the resist pattern R2 (FIG. 15), blasting is performed with the metal foil 65 used as a mask to expose the sacrificial pattern VP1 (FIG. 16). Then, after removal of the metal foil 65 (FIG. 17), laser machining is performed to form an opening 52a in the interlayer insulating film 52 (FIG. 18). Through the above processes, formation of the conductor layer 10 and interlayer insulating film 52 is completed.

Thereafter, by repeating the processes illustrated in FIGS. 7 to 18, the conductor layer 20, interlayer insulating film 53, conductor layer 30, and interlayer insulating film 54, and conductor layer 40 are sequentially formed (FIG. 19). The conductor layers 20, 30, and 40 include respectively sacrificial patterns VP2 to VP4 overlapping the sacrificial pattern VP1. Then, the interlayer insulating film 55 that covers the conductor layer 40 is formed (FIG. 20). The interlayer insulating film 55 can be formed by applying a resin material blended with magnetic filler. Then, the interlayer insulating film 55 is patterned to expose the sacrificial pattern VP4 (FIG. 21). In this state, wet-etching is performed to remove the sacrificial patterns VP1 to VP4 (FIG. 22). The coil patterns CP1 to CP4 are covered with the interlayer insulating films 51 to 55 and are thus not etched. As a result, a space S is formed so as to extend over the inner diameter areas of the coil patterns CP1 to CP4.

Then, the magnetic element members M1 and M3 are formed to fill the space S (FIG. 23). Then, the metal foils 62 and 63 are peeled off at the interface therebetween to remove the support 60. Then, after inverting up and down, a support 70 is stuck (FIG. 24), followed by removal of the metal foil 63 by etching (FIG. 25). In this state, aching is performed to reduce the film thickness of the interlayer insulating film 51 as a whole (FIG. 26). The reduction amount of the film thickness is controlled to take such a value that the small thickness area 51B is completely removed, while the large thickness area 51A remains. As a result, the magnetic element member M1 filled in the inner diameter area of the coil part C is exposed.

Then, the magnetic element member M2 is formed so as to cover the interlayer insulating film 51 (FIG. 27). Then, the support 70 is peeled off, and dicing is performed for singulation, whereby the coil component 1 according to the present invention illustrated in FIG. 1 is completed.

As described above, in the present embodiment, the interlayer insulating film 55 is formed by applying a resin material blended with magnetic filler, so that it is possible to achieve a high inductance value without increasing the entire thickness as compared to a case where all the interlayer insulating films 51 to 55 are made of a nonmagnetic material.

Further, in the present embodiment, the interlayer insulating film 51 is laminated on the surface of the metal foil 63 having the protruding part 63a, thus allowing the shape of the protruding part 63a to be transferred to the interlayer insulating film 51. As a result, the interlayer insulating film 51 has the large thickness area 51A and small thickness area 51B, so that the film thickness thereof can be further reduced by the asking (FIG. 26). This can reduce the height of the coil component 1.

While the preferred embodiment of the present invention has been described, the present invention is not limited to the above embodiment, and various modifications may be made within the scope of the present invention, and all such modifications are included in the present invention.

REFERENCE SIGNS LIST

- 1 coil component

 What is claimed is:
 1. A coil component comprising: a coil part having a structure in which a plurality of interlayer insulating films and a plurality of spirally wound coil patterns are alternately stacked in an axial direction; and a magnetic element member embedding therein the coil part, wherein the plurality of interlayer insulating films include a first interlayer insulating film covering, from one end side in the axial direction, a first coil pattern of the plurality of coil patterns that is positioned at the one end in the axial direction and second interlayer insulating films covering remaining coil patterns of the plurality of coil patterns, wherein the first interlayer insulating film is higher in permeability than the second interlayer insulating films, wherein the magnetic element member is higher in permeability than the first interlayer insulating film, wherein the plurality of interlayer insulating films further includes a third interlayer insulating film covering, from other end side in the axial direction, a second coil pattern of the plurality of coil patterns that are positioned at the other end in the axial direction, and wherein the third interlayer insulating film is higher in permeability than the second interlayer insulating film.
- 5 10 15 20 25 30 35 40 45 50 55
- second coil pattern of the plurality of coil patterns that are positioned at the other end in the axial direction, and wherein the third interlayer insulating film is higher in permeability than the second interlayer insulating films.
 2. The coil component as claimed in claim 1, wherein the first interlayer insulating film is made of a same material as the magnetic element member.
 3. The coil component as claimed in claim 1, wherein the first interlayer insulating film is made of a magnetic resin material obtained by adding magnetic filler to a resin material, and wherein a maximum particle size of the magnetic filler is smaller than a pattern interval of the first coil pattern.
 4. The coil component as claimed in claim 3, wherein the magnetic filler contains nanofiller made of a magnetic metal member having a mean particle size of 1 μ m or less.
 5. The coil component as claimed in claim 3, wherein the first coil pattern is tapered such that a cross section of the first coil pattern is narrower toward the one end side in the axial direction.
 6. The coil component as claimed in claim 1, wherein the coil part includes an electrode pattern positioned in a same conductor layer as the first coil pattern, and wherein the electrode pattern contacts the first interlayer insulating film and is exposed from the magnetic element member.
 7. A method for manufacturing a coil component, the method comprising:
 a first step of alternately stacking a plurality of interlayer insulating films and a plurality of spirally wound coil patterns in an axial direction to form a coil part; and a second step of embedding the coil part in a magnetic element member,
 wherein the plurality of coil patterns includes a first coil pattern to be formed last and remaining second coil patterns, wherein the plurality of interlayer insulating films include first and second interlayer insulating films, wherein the first step includes a step of alternately forming the second coil patterns and the second interlayer insulating films and a step of, after forming the first coil pattern, covering the first coil pattern with the first interlayer insulating film, wherein the first interlayer insulating film is higher in permeability than the second interlayer insulating films,
 wherein the magnetic element member is higher in permeability than the first interlayer insulating film, wherein the plurality of interlayer insulating films further includes a third interlayer insulating film covering, from other end side in the axial direction, a second coil pattern of the plurality of coil patterns that are positioned at the other end in the axial direction, and wherein the third interlayer insulating film is higher in permeability than the second interlayer insulating film.
